ABSTRACT

A process for preparing clear bright oleaginous aluminum dispersions comprising admixing an oil soluble dispersing agent, an oleaginous carrier and a volatile solvent with a dispersible alumina, heating and recovering a clear bright oleaginous aluminum dispersion.

13 Claims, No Drawings

PROCESS FOR PREPARING CLEAR BRIGHT OLEAGINOUS ALUMINUM DISPERSIONS

This application is a continuation-in-part of U.S. Ser. No. 230,065 now abandoned of the same title filed Feb. 28, 1972.

BACKGROUND OF THE INVENTION

1. Field of the Invention

This invention relates to the dispersion of metals in oleaginous materials. This invention further relates to a process for dispersing aluminum in oleaginous materials. This invention further relates to a process for dispersing aluminum in oleaginous materials by the use of sulfonic acids and carboxylic acids as dispersing agents.

2. Brief Description of the Prior Art

It has been known heretofore that dispersions of aluminum in oleaginous materials can be prepared by a variety of methods. Several such methods are shown in the following references which were considered in the prior art search conducted on the concept of the present invention.

U.S. Pat. No. 2,585,520 issued Feb. 12, 1952, to Van Ess et al.; U.S. Pat. No. 2,676,925 issued Apr. 27, 1954 to Lindstrom et al.; U.S. Pat. No. 3,018,172 issued Jan. 23, 1962 to Tillman; U.S. Pat. No. 3,061,419 issued Oct. 30, 1962 to Sias et al.; U.S. Pat. No. 3,149,074 issued Sept. 15, 1964 to Tillman; Australian Patent No. 200,149 issued to Garner et al. and published May, 1955; and Belgium Patent No. 498,777 issued to Fagerholt et al. and published February 15, 1951. The references considered most relevant are U.S. Pat. No. 3,018,172 and Australian Patent No. 200,149.

U.S. Pat. No. 3,018,172 to Tillman shows a process for preparing dispersions of aluminum in mineral oils and the like by a process wherein aluminum alkoxide is dispersed in an alkanol, mixed with a mineral oil containing an oil soluble detergent material such as sulfonate materials and thereafter hydrolyzed to produce a dispersion of alumina. The process requires a hydrolysis step in an oil media which necessitates mixing an aqueous portion with an oily portion and, of course, subsequent separation of the aqueous and oily portions.

Australian Patent 200,149 discloses a process for dispersing alumina in oleaginous materials containing sulfonic acids by a mechanical milling technique; however, the dispersions obtained are not shown to be clear high quality dispersions but rather are primarily intended for use as fuel oil additives and the like.

Accordingly, much time and effort has been devoted to a search for a better method for preparing dispersions of aluminum in oleaginous materials whereby such products may be produced by simpler methods and of an improved quality.

OBJECTS OF THE INVENTION

It is an object of the present invention to provide a simplified method for preparing an aluminum dispersion in oleaginous materials.

It is a further objective of the present invention to provide a method whereby clear bright aluminum dispersions in oleaginous materials may be prepared.

SUMMARY OF THE INVENTION

It has now been found that the objectives of the present invention are achieved by admixing an oil soluble dispersing agent selected from the group consisting of

oil soluble sulfonic acids in which the hydrocarbon portion has a molecular weight from about 300 to about 1000 and carboxylic acids containing at least about 8 carbon atoms, an oleaginous carrier and a volatile solvent with alumina prepared by the water hydrolysis of aluminum alkoxides and having the following properties:

10	(1) crystal structure - alpha alumina monohydrate	
	(2) crystal structure after calcining to 900°F.	-
	(3) Ultimate crystal size (x-ray diffraction)	
	020 reflection	30-70A
	021 reflection	60-110A
15	(4) pore volume	0.35-0.65 cc/g
	(5) loose bulk density	35-70 lb/ft ³
	(6) particle size (sieve)	
	>45 micron - 20%	
	<45 micron - 80%	
	(7) Al ₂ O ₃ content	65-85 wt. %
	(8) Loss on ignition	15-35 wt. %
	(9) Surface Area	150-350 in ² /g.

to form a mixture of uniform consistency and thereafter heating said mixture to substantially remove all of said volatile solvent and recovering clear bright aluminum containing dispersions.

PREFERRED EMBODIMENTS

Aluminum dispersions in oleaginous materials such as those produced by the process of the present invention are useful as fuel oil additives, jet fuel additives, motor fuel additives, lubricant additives and the like. The dispersions of the present invention are particularly useful since such dispersions contain substantial amounts of aluminum in a clear bright dispersion suitable for use in high quality motor oils and the like.

According to the process of the present invention, aluminum containing dispersions are prepared by admixing an oil soluble dispersing agent, an oleaginous carrier, and a volatile solvent with a dispersible alumina and heating the mixture to remove said volatile solvent and recover the aluminum containing dispersion.

Suitable oil-soluble dispersing agents include the oil-soluble sulfonic acids and carboxylic acids. The term "oil-soluble sulfonic acids", as used herein, refers to those materials wherein the hydrocarbon portion of the molecule has a molecular weight in the range of about 300 to about 1,000. Preferably, this molecular weight is in the range of about 370 to about 700. These oil-soluble sulfonic acids can be either synthetic sulfonic acids or the so-called mahogany or natural sulfonic acids. The term "mahogany sulfonic acid" is believed to be well understood, since it is amply described in the literature. The term "synthetic sulfonic acids" refers to those materials which are prepared by sulfonation of hydrocarbon feedstocks which are prepared synthetically. The synthetic sulfonic acids can be derived from either alkyl or alkaryl hydrocarbons. In addition, they can be derived from the hydrocarbons having cycloalkyl (i.e. naphthenic) groups in the side chains attached to the benzene ring. The alkyl groups in the alkaryl hydrocarbons can be straight or branched chain. The alkaryl radical can be derived from benzene, toluene, ethyl benzene, xylene isomers, or naphthalene.

An example of a hydrocarbon feedstock which has been particularly useful in preparing synthetic sulfonic acids is a material known as postdodecylbenzene. Postdodecylbenzene is a bottoms product of the manufacture of dodecylbenzene. The alkyl groups of postdode-

cylbenzene are branched chain. Postdodecylbenzene consists of monoalkylbenzenes and dialkylbenzenes in the approximate mole ratio of 2:3 and has typical properties as follows:

Specific gravity at 38°C.	0.8649
Average molecular weight	385
Percent sulfonatable	88
A.S.T.M. D-158 Engler:	
I.B.P., °F.	647
5 °F.	682
50 °F.	715
90 °F.	760
95 °F.	775
F.B.P. °F.	779
Refractive Index at 23°C.	1.4900
Viscosity at:	
-10°C., centistokes	2,800
20°C., centistokes	280
40°C., centistokes	78
80°C., centistokes	18
Aniline point, °C.	69
Pour Point, °F.	-25

An example of another hydrocarbon feedstock which is particularly useful in preparing synthetic sulfonic acids is a material referred to as "dimer alkylate". Dimer alkylate has a long, branched-chain alkyl group. Briefly described, dimer alkylate is prepared by the following steps:

1. dimerization of a suitable feedstock, such as cat poly gasoline, and
2. alkylation of an aromatic hydrocarbon with the dimer formed in step (1).

Preferably, the dimerization step uses a Friedel-Crafts alkylation sludge as the catalyst. This process and the resulting product are described in U.S. Pat. No. 3,410,925, issued Nov. 12, 1968 to Eby et al. In order to make my disclosure even more complete, U.S. Pat. No. 3,410,925 is made a part of this disclosure.

The oil-soluble sulfonic acids are preferred for use in my process.

In addition to the sulfonic acids derived from the foregoing-described hydrocarbon feedstock, examples of other suitable sulfonic acids include the following: mono- and poly-wax-substituted naphthalene sulfonic acid, dinonyl naphthalene sulfonic acid, diphenyl ether sulfonic acid, naphthalene disulfide sulfonic acid, dicetyl thianthrene sulfonic acid, dilauryl beta-naphthol sulfonic acid, dicapryl nitronaphthalene sulfonic acid, unsaturated paraffin wax sulfonic acid, hydroxy substituted paraffin wax sulfonic acid, tetraamylene sulfonic acid, mono- and poly-chloro-substituted paraffin wax sulfonic acid, nitrosoparaffin wax sulfonic acid; cycloaliphatic sulfonic acid such as lauryl-cyclohexyl sulfonic acid, mono- and poly-wax-substituted cyclohexyl sulfonic acid, and the like.

Suitable carboxylic acids which can be used in preparing the aluminum dispersions include napthenic acids, such as the substituted cyclopentane monocarboxylic acids, the substituted cyclohexane monocarboxylic acids and the substituted cyclohexane monocarboxylic acids and the substituted aliphatic polycyclic monocarboxylic acids containing at least 15 carbon atoms. Specific examples include cetyl cyclohexane carboxylic acids, dioctyl cyclopentane carboxylic acids, dilauryl decahydronaphthalene and stearyl-octahydro indene carboxylic acids and the like and oil-soluble salts thereof. Suitable oil-soluble fatty acids are

those containing at least about 8 carbon atoms. For producing the dispersions of this invention in liquid form, I prefer fatty acids which are liquids at ambient temperatures down to about 15°C. Specific examples

5 include 2-ethyl hexanoic acid, pelargonic acid, oleic acid palmitoleic acid, linoleic acid and riconoleic acid. Naturally occurring mixtures of predominantly unsaturated fatty acids, such as tall oil fatty acids, are particularly suitable. Examples of commercially available tall 10 oil fatty acids include the "Crofatols", available from Crosby Chemical Company and the "Acintols", available from Arizona Chemical Company.

A wide variety of oleaginous carriers are suitable in the process of my invention. The principal requisites in 15 the oleaginous carrier are that it acts as a solvent for the dispersing agent used, has a viscosity from about 60 to about 500 SUS at 100°F and has a boiling point of at least 160°C. at normal atmospheric pressure. Suitable oleaginous carriers include materials boiling in the lubricating oil range and lower boiling refinery hydrocarbon streams, such as Stoddard solvent and diesel fuels. Examples of nonvolatile diluents boiling in the lubricating oil range which can be used include mineral lubricating oils obtained by any of the conventional refining procedures; synthetic lubrication oils, such as polymers of propylene, polyoxyalkylenes, polyoxypropylene, dicarboxylic acid esters, and esters of phosphorus; synthetic hydrocarbon lubricating oils, such as dialkylbenzenes, diphenylalkanes, alkylated tetrahydro-naphthalenes, and mixtures of these materials; vegetable oils, such as corn oil, cotton seed oil, and castor oil; and animal oils, such as lard oil and sperm oil. Of the nonvolatile diluents described hereinbefore, the mineral lubricating oils and the synthetic lubricating oils are considered more suitable, with the mineral lubricating oils being preferred.

25 Volatile solvent as used herein refers to hydrocarbon solvents having a boiling point at normal atmospheric pressure of less than about 300°F. Some specific examples of such solvents are: petroleum naptha, hexane, heptane, octane, benzene, toluene, glycol ethers, monohydric alcohols containing from about 1 to about 6 carbon atoms and the like. Very desirable solvents 30 are hexane, heptane, benzene, butanol and the mono-methyl ether of ethylene glycol.

35 The dispersible alumina useful in the process of the present invention is prepared by the water hydrolysis of aluminum alkoxides prepared by the Ziegler process to 40 produce an organic portion and an aluminum slurry portion. The alumina slurry portion is further purified and dried. Careful control of this process results in alumina which can be used to prepare the oil soluble dispersions of the present invention. Such an alumina is 45 marketed by Continental Oil Company of 30 Rockefeller Plaza, New York, N.Y. under the trademark "DISPAL". The physical properties of such alumina are typically as follows:

- 60 (1) crystal structure - alpha alumina monohydrate
- (2) crystal structure after calcining to 900°F - gamma alumina
- (3) Ultimate crystal size (x-ray diffraction)

020 reflection	30-70Å
021 reflection	60-110Å
- (4) Pore volume
- (5) loose bulk density
- (6) particle size (sieve)

>45 micron - 20%	0.35-0.65 cc/g
<45 micron - 80%	35-70 lb/ft ³

-Continued

(7) Al_2O_3 content	65-85 wt. %
(8) Loss on ignition	15-35 wt. %
(9) Surface Area	150-350 $\text{in}^2/\text{g.}$

It has been found that uniquely desirable aluminum dispersions are produced by the process of the present invention when such alumina is used. Tests with other alumina products has failed to yield comparable products as will be shown in the examples hereinafter.

As will be apparent to those skilled in the art the process of the present invention can be carried out using only the alumina and oil soluble dispersing agent, however, it is expected that great difficulty will be obtained in admixing the components and the like. Similarly the volatile solvent may be omitted, however, it has been found that the addition of such solvents is beneficial in achieving intimate mixing of the components, reduction of viscosity during processing and the like. While such modifications are possible, it is pointed out that the preferred practice of the present invention is accomplished by the admixture of the oil soluble dispersing agent, the oleaginous carrier and volatile solvent prior to the addition of the alumina. Following the addition of the alumina further mixing of the components is desirable prior to heating the mixture to remove the solvent by distillation. Optionally, an inert stripping gas may be used in the latter stages of the heating operation to improve the effectiveness of the distillation in removing the last traces of the organic solvent.

The addition of from about 1 to about 20 weight percent water, based on the alumina added is beneficial. The process is equally effective without the addition of water but the water apparently aids in obtaining desirable aluminum dispersion and is readily removed with the volatile solvent as overhead during the heating step. Very desirable results have been obtained when about 10 weight percent water was used. The process as noted above is equally effective with no water present and the use of water will be found most desirable in those embodiments wherein the increased ease in dispersing the alumina offsets the added load on heating and solvent recovery equipment.

When proper amounts of alumina are added, the product may be recovered directly from the distillation vessel after removal of the volatile solvent. In many applications it may be desirable to add an excess of alumina to achieve a maximum dispersion of aluminum in the end product. In such instances, it would be desirable to use a filtration step to obtain the clear bright product. The aluminum dispersions so produced contain up to about 20 weight percent aluminum. While we do not wish to be bound by any particular theory, it is believed that portions of the aluminum are present as the aluminum sulfonate and the remaining portions are present as dispersions of alumina.

As noted herebefore the aluminum dispersions so produced contain up to about 20 weight percent aluminum. Those dispersions containing more than about 6 weight percent aluminum are preferred since less of the dispersion is required to incorporate a given amount of aluminum into blends to which the dispersion is added. In many applications those dispersions containing more than 10 weight percent aluminum are preferred. A preferred range is from 8 to about 20 weight percent aluminum.

Numerous modifications and variations of the above process are possible within the scope of the present in-

vention and may appear obvious or desirable to those skilled in the art based upon a review of the preceding description of the preferred embodiments and the following examples and claims

EXAMPLE I

A 7000 gallon vessel equipped with a top entering mixer, internal coils, overhead heat exchangers, entry lines etc. was charged with 1900 gallons of sulfonic acid dissolved in hexane. The charge material had the following properties:

(a) specific gravity	6.287 lb/gal
(b) sulfonic acid content	24.6 wt. %
(c) oil content (100 SUS paraffinic)	9.1 wt. %
(d) water content	1.0 wt. %
(e) hexane content	65.3 wt. %
(f) average sulfonic acid molecular weight	455

The sulfonic acid was derived from a mixture of synthetic alkylbenzenes consisting of 35 weight percent monoalkylbenzene derived from a straight chain mono olefin and having an average molecular weight of about 420, 15 weight percent mono-alkylbenzene derived from a branched chain mono olefin and having an average molecular weight of about 379 and 50 weight percent dialkylbenzene derived from straight chain mono olefins and having an average molecular weight of about 370. An additional 250 gallons of hexane was added. The mixer was then turned on and 46 gallons of water was added followed by the addition of 3900 lbs of DISPAL alumina with continued mixing for about 30 minutes. The mixture was then heated to reflux and maintained at reflux for about 2.75 hours. 404 gallons of a 300 SUS naphthenic oil was then added and the solvents, i.e. hexane and water were removed as overhead by heating to 300°F. Carbon dioxide stripping gas was introduced at 150 cubic feet per minute during the latter stages of the heating step. The product remaining in the vessel weighed 9250 lbs and was a bright, clear, liquid dispersion containing 29 wt % aluminum sulfonate, 38 weight percent naphthenic oil and 33 weight percent $\text{Al}_2\text{O}_3 \cdot \text{H}_2\text{O}$.

EXAMPLE II

A one liter vessel was charged with 116.7 grams of sulfonic acid dissolved in 400 grams of hexane. The acid was derived in the same manner as that used in Example I. 37.9 grams of 80 SUS neutral oil commonly described as 80 pale oil was added to the mixture and thereafter 12.5 grams of DISPAL alumina was added. The mixture was stirred well for about 30 minutes at room temperature and then heated to about 150°C for about 20 minutes. Nitrogen gas was admitted as a stripping gas in the latter part of the heating step. The product remaining in the bottom of the vessel weighed 94.8 grams and had the following properties: 30 weight percent aluminum sulfonate, 4.8 weight percent aluminum, 0.32 percent BS&W and electron micrograph tests disclosed that the average particle size was less than 0.1 micron with the majority of particles being 0.01 micron or less.

EXAMPLE III

Similar tests were run using other alumina products. The test results and alumina properties are shown in Table 1.

Table 1

Alumina Properties	Sample Number					
	1	2	3	4	5	6
Pore Volume (cc/g)	0.55	1.20	0.53	1.90	0.87	0.71
Surface Area (m ² /g)	200	300	274	350	118	250
Loose bulk density (lb/ft ³)	55	20	28	11	24	31
*Al ₂ O ₃ (wt. %)	75	72	70	79	85	75
Aluminum Dispersion Properties						
% BS&W	0.2	22	8	100	1	24
Appearance	Bright and Clear	Cloudy	Solid	Cloudy	Very Milky	Cloudy

*Alumina is generally used to refer to an apparently dry solid or powder which usually contains some free water, water of hydration and the like as well as Al₂O₃.

Sample No. 1 was DISPAL alumina. Sample No. 2 was an alumina marketed by Kaiser Chemical Co., P. O. Box 1031, Baton Rouge, La., under the trademark "KCSA" and has the properties shown. Sample No. 3 was alumina marketed by E. I. Du Pont de Nemours & Co. Inc., Wilmington 98, Del. under the trademark "BAYMAL" and has the properties shown. Sample 4 was alumina prepared by the water hydrolysis of alumina alkoxides and thereafter contacted with methyl alcohol and dried. The product alumina had the properties shown above. Sample 5 was prepared by the water hydrolysis of alumina alkoxides followed by purification and aging with heat prior to drying. The properties were as shown in Column 5. Sample 6 was a mixture of 75% DISPAL alumina and 25% BAYMAL alumina. A slurry of the mixture was spray dried to produce an alumina product having the properties shown above.

It is obvious from the Table the only alumina tested which produces a bright clear dispersion wherein the alumina is fully dispersed is the test wherein DISPAL alumina was used.

Having thus described the invention, I claim:

1. A process for preparing clear, bright aluminum-containing dispersions containing at least 6 weight percent aluminum, said process comprising:

a. admixing an oil soluble dispersing agent, selected from the group consisting of oil soluble sulfonic acids in which the hydrocarbon portion has a molecular weight between about 350 and 1000 and hydrocarbyl carboxylic acids containing at least 8 carbon atoms, an oleaginous carrier selected from the group consisting of mineral lubricating oils, synthetic lubricating oils, vegetable oils and animal oils and a volatile hydrocarbon solvent having a boiling point at atmospheric pressure below about 300°F. with alumina prepared by the water hydrolysis of aluminum alkoxides and having the following properties:

- (1) Crystal structure - alpha alumina monohydrate
- (2) Crystal structure after calcining to 900°F - gamma alumina
- (3) Ultimate crystal size (x-ray diffraction)

020 reflection	30-70 Å
021 reflection	60-110 Å
- (4) Pore volume 0.35-0.65 cc/g
- (5) Loose bulk density 35-70 lb/ft³
- (6) Particle size (sieve)

> 45 micron - 20%	
< 45 micron - 80%	
- (7) Al₂O₃ content 65-85 wt. %
- (8) Loss on Ignition 15-35 wt. %
- (9) Surface Area 150-350 m²/g

to form a mixture of uniform consistency;

- b. heating said mixture to remove substantially all of said volatile hydrocarbon solvent; and
- c. recovering said clear bright aluminum-containing dispersion.

2. The process of claim 1 wherein from about 1 to about 20 weight percent water, based on the alumina added is included in the mixture.

3. The process of claim 1 wherein said hydrocarbon portion of the sulfonic acid has an average molecular weight between about 370 and 700.

4. The process of claim 1 wherein said carboxylic acid is selected from the group consisting of naphthenic acids, hydrocarbyl substituted cyclohexane monocarboxylic acids, hydrocarbyl substituted polycyclic hydrocarbyl monocarboxylic acids containing at least 15 carbon atoms and naturally occurring mixtures of predominantly unsaturated fatty acids.

5. The process of claim 1 wherein said dispersions contain from 8 to about 20 weight percent aluminum.

6. The process of claim 1 wherein said volatile solvent is selected from the group consisting of petroleum naptha, hexane, heptane, octane, benzene, toluene, glycol ethers and monohydric alcohols containing from about 1 to about 6 carbon atoms.

7. The process of claim 5 wherein said volatile solvent is selected from the group consisting of hexane, heptane, benzene, butanol and the monomethyl ethers of ethylene glycol.

8. The process of claim 1 wherein said oleaginous carrier is selected from mineral lubricating oils, and synthetic lubricating oils.

9. The process of claim 1 wherein stripping gas is introduced during the latter portion of the heating step to further remove said volatile solvent.

10. The process of claim 1 wherein said oil soluble dispersing agent is an oil soluble sulfonic acid having an average molecular weight of about 420, said volatile solvent is hexane, said oleaginous carrier is 80 pale oil, said heating is conducted at 150°C for about 20 minutes and nitrogen is introduced as a stripping gas during the heating step.

11. The process of claim 10 wherein water is added to the mixture in an amount equal to about 10 weight percent of the alumina added.

12. Clear bright aluminum-containing dispersions containing at least about 6 weight percent aluminum dispersed in an oil-soluble dispersing agent selected from the group consisting of oil-soluble sulfonic acids

in which the hydrocarbon portion has a molecular weight between about 350 and 1000 and hydrocarbyl carboxylic acids containing at least 8 carbon atoms, and an oleaginous carrier selected from the group consisting of mineral lubricating oils, synthetic lubricating oils, vegetable oils and animal oils, prepared by the process of claim 1.

13. The dispersion of claim 12 wherein said aluminum is present in a form selected from salts of said sulfonic acids, salts of said hydrocarbyl carboxylic acids and alpha alumina monohydrate and in an amount equal to 8 to about 20 weight percent of the dispersion.

* * * * *
